SPILLWAY FOR DAMS

Filed May 26, 1925

Fig. 1

UNITED STATES PATENT OFFICE.

JOHN F. VAUGHAN, OF CAMBRIDGE, MASSACHUSETTS.

SPILLWAY FOR DAMS.

Application filed May 26, 1925. Serial No. 32,915.

The present invention relates to dams and more particularly to spillways and wasteways for the same.

It is common practice in dam construction to provide for the discharge of surplus water by means of a spillway extending lengthwise of the dam a sufficient distance to give the required discharge capacity. Such a construction ordinarily involves the use of abutments in the body of the dam adjacent the spillway section. The relative cost of such a spillway of concrete or masonry with its abutments is high, and when the dam is of earth may constitute a large proportion of the cost of the entire dam, especially where a considerable length of spillway is required.

It is one of the objects of the present invention to provide a spillway construction which shall have a greatly increased effective discharge length relative to its width measured lengthwise of the dam as compared with prior constructions, thus making it possible to obtain the required length of spillway where there would be insufficient space for the ordinary spillway across the stream, and also making it possible to increase the discharge capacity to such an extent that the normal pond level may be raised without, however, raising the maximum level.

It is another object of the present invention to provide a spillway and wasteway which may be constructed at a relatively low cost, owing to the fact that a much less expensive type of construction may be employed; and further, on account of the short length of the body of the dam occupied by the spillway and wasteway section, a greater proportionate length of regular dam structure may be used, which, in the case of earth dams, affords opportunity for large savings.

Still another object is to so construct the spillway that the energy of the waste water will be largely dissipated and liability of damage to the wasteway and to the stream below will be lessened.

Other objects are to provide a spillway and wasteway which may be protected from the weather and from liability of freezing, and further, which will clear itself of ice, logs, or other similar materials.

With these objects in view the present invention consists of the structures and combinations of structures hereinafter de-

scribed and more particularly defined in the claims.

In the accompanying drawings which illustrate what is now considered to be the preferred form of the present invention, Figure 1 is a top plan view of a transverse section of earth dam provided with my improved spillway and wasteway construction; Fig. 2 is a vertical section of the same transversely of the dam; Fig. 3 is a vertical transverse section of the spillway on lines 3-3 of Fig. 2 looking in the direction of the arrows; Fig. 4 is a vertical section of the wasteway on lines 4-4 of Fig. 2 looking in the direction of the arrows; and Fig. 5 is a vertical section transversely of the dam showing a modified construction.

The dam illustrated in the drawings is of the conventional earth type having the front sloping face 1, the rear sloping face 2, and the flat top portion 3. The spillway and the wasteway which in the drawings are shown as integrally constructed of concrete, consist of a relatively narrow deep structure extending from the front face 1 of the dam upstream into the pond or reservoir and downstream through the body of the dam and back face 2. The spillway portion, indicated generally by the reference character 5, comprises the side walls 6 converging upstream in horizontal plan, as shown in Fig. 1, and joined at their upstream ends by the end wall 7. These side walls 6 rise from the horizontal foundation or base 8 (see Fig. 3), slightly diverging to form a structure substantially V or rather U-shaped in vertical cross-section, the tumble bay at the bottom of the spillway being rounded for a purpose later to be described. The end wall 7 rising from the front end of the base 8 is inclined upstream for the greater portion of its height, the extreme top part, however, being vertical as shown in Fig. 2, and extending well above the top surfaces or crests 9 of the sides of the spillway over which crests the waste water flows. The purpose of such extension is to prevent the flow of water over the end wall 7 thus avoiding a plunging concentration or excess of flow at the end of the spillway with the resulting piling up of the overfalling stream, a depression in the water surface in the tumble bay where it strikes, and a standing wave further down stream.

In order to reinforce and strengthen the side walls of the spillway, buttresses or abutments 11 are formed at intervals along the outer surfaces of the sides 6, and depending diaphragm walls 12 are provided in line with such buttresses and extending downwardly from the base 8 into the earth formation. These buttresses and diaphragm walls have the further function of preventing creepage of water along the outer or back surface of the walls and beneath the base or foundation.

Owing to the relatively narrow construction of the spillway and wasteway it is possible to brace the side walls 6 by struts 14 placed between them, thus bringing the earth and water pressures behind the walls through the dam and in the pond in direct opposition and permitting the use of thin curtain walls for both spillway and wasteway instead of heavy gravity or buttressed sections. As shown in the drawings, two rows of struts 14 are provided which are located in line with the buttresses 11. The tops of the struts, which are of inverted V-shape, are shod with steel to protect them from damage by falling ice, logs, or other material in the waste water.

The wasteway, shown generally by the reference character 15, is formed integrally with the spillway, extending from the rear end of the latter through the body of the dam. Like the spillway, it comprises the sloping side walls 17, braced from one another by the struts 18, which have their upstream faces V-shaped and protectively shod with steel.

In certain localities, and under certain conditions, it may be necessary to weather-proof or otherwise protect the spillway and wasteway, as for example, from freezing in the extreme cold of the northern latitudes. Accordingly, a closure or roof 20 may be provided, as shown in Figs. 2, 3 and 4, which covers the spillway and wasteway with the exception of the extreme downstream end. This closure is supported over the spillway by means of the front wall 7 and piers 21 rising from the crests of the side walls 6. On the wasteway the roof or closure rests directly upon the tops of the side walls 17.

In order to close the entrance and exit opening for the wasteway they are provided with swinging gates hung upon the horizontal pivots and automatically opening by the pressure of the water. These gates 22 at the spillway open inwardly to permit the water to flow over the crests of the side walls 6 of the spillway. The gate 23 at the downstream end of the wasteway opens outwardly to permit the discharge of the waste water.

By providing these automatic closures for the spillway and wasteway, the liability of the spillway and wasteway being choked or closed by ice is greatly reduced, if not en-

tirely avoided, since the temperature within the body of the dam will remain relatively high provided the free circulation of air is prevented.

In Fig. 5 is shown a modified construction in which, instead of providing a roof or cover for the entire spillway and wasteway, a horizontal diaphragm 25 is provided which not only takes the place of one row of struts for bracing the side walls 17 from one another, but which also prevents the formation of ice on the bottom of the spillway. If, for any reason, the passage or tunnel beneath the diaphragm should become choked, the water is free to flow over the top of the diaphragm.

It will be noted that my improved spillway construction extending from the face of the dam upstream into the pond provides a maximum of spillway length for a minimum of width for the spillway and wasteway, as measured lengthwise of the dam. Thus a higher normal pond level may be safely employed with the consequent advantages of a higher stratum of water, yet without using flash-boards or gates, either manually or power operated or automatic.

My improved spillway is of relatively cheap construction since the usual long masonry spillway may be shortened and the volume of masonry reduced and replaced by relatively less expensive earth fill, and the bracing of one wall from the other permits relatively thin curtain walls to be employed without impairing the strength of the structure.

Furthermore, by conforming the inner surfaces of the spillway crests to the natural curvature of the nap of the overflow of water, and by rounding the bottom of the tumble bay, the waste water flows over the opposed walls of the spillway in smooth, even streams or sheets which are brought into direct impact with each other, thereby absorbing to a large degree the kinetic energy of the falling water and permitting a relatively slow flow through and out of the wasteway, thus avoiding the objectionable erosive effects of a high velocity discharge.

In the preferred construction the spillway is substantially V-shaped in horizontal plan, thus providing a progressively greater downstream capacity to take care of the progressively greater amounts of waste water to be handled. Furthermore, both the spillway and the wasteway are V-shaped in vertical cross-section, thus tending to be self-clearing of obstructions by providing greater proportionate capacity for the upper than the lower portions thereof.

While in the drawings I have shown what I consider to be the preferred construction, it is to be understood that my invention is not necessarily limited thereto except where so specifically defined in the claims, but may

be embodied in other formations and constructions. For example, the wasteway is illustrated as extending upward to the surface of the top and downstream slope of the dam, but this is not essential, it being only necessary that the wasteway extend upward sufficiently to provide a conduit of the necessary capacity.

Having thus described the invention, what is claimed is:

1. The combination with a dam, of a spillway for the same comprising spaced, opposed walls which extend upstream from the face of the dam and over which the water flows in opposing streams, struts between the opposed walls, and a conduit connected with the spillway and extending through the dam for the water flowing over the spillway.
2. The combination with a dam, of a spillway for the same comprising opposed walls which extend upstream from the face of the dam and over which the water flows, struts between the opposed walls, and a conduit connected with the spillway and extending through the dam to discharge the water flowing over the spillway.
3. The combination with a dam, of a spillway for the same comprising a spillway wall which extends upstream from the face of the dam and over which the water flows, a second wall which extends upstream and from which the spillway wall is spaced to form a water discharge passage therebetween, struts between the two walls, and a conduit connected with the spillway and extending through the dam for the waste water flowing over the spillway.
4. The combination with a dam, of a spillway comprising opposed walls over which the water flows, extending upstream from the face of the dam and converging in plan view, struts between the walls, and a conduit connected with the spillway and extending through the dam for the water flowing over the spillway.
5. The combination with a dam, of a spillway comprising walls over which the water flows, extending upstream from the face of the dam and upwardly diverging in vertical cross-section, and a conduit connected with the spillway and extending through the dam for the water flowing over the spillway.
6. The combination with a dam, of a spillway comprising opposed walls over which the water flows, extending upstream from the face of the dam, converging in plan and upwardly diverging in vertical cross-section, struts between the walls, and a conduit connected with the spillway and extending through the dam for the water flowing over the spillway.
7. The combination with a dam, of a narrow wasteway extending through the

dam, the sides of the wasteway projecting upstream from the face of the dam to form a spillway.

8. The combination with a dam, of a narrow wasteway extending through the dam, the sides projecting upstream from the face of the dam to form a spillway, and compression members between the sides.

9. The combination with a dam, of a narrow wasteway extending through the dam and upstream from the face of the dam to form a spillway, a roof over the spillway spaced therefrom to provide an opening for the flow of water over the spillway, and swinging gates for said opening.

10. The combination with a dam, of a narrow wasteway extending through the dam, the sides of the wasteway projecting upstream to form a spillway, struts between the sides of the wasteway and spillway, the struts having a V-shaped face, and metal shoes for protecting said faces.

11. The combination with a dam, of a spillway for the same comprising opposed side walls over the crests of which the water flows, the walls extending upstream from the face of the dam and being spaced to form a narrow passage for the discharge of the waste water, an end wall joining the side walls and rising above the crests of the latter to prevent the discharge of waste water over the end wall, and a conduit connected with the spillway and extending through the dam to discharge the water flowing over the spillway.

12. The combination with a dam, of a narrow wasteway extending through the dam, with its sides projecting upstream from the face of the dam to form the sides of a spillway over the crests of which the water flows, an end wall joining the side walls and rising above the crests of the side walls, supports rising from said crests, a roof carried by the end wall and the supports, inwardly swinging gates pivoted upon horizontal axes and tending to close by gravity the inlet openings between the crests and the roof, a roof for the wasteway, and an outwardly swinging gate pivoted on a horizontal axis and tending to close by gravity the outlet end of the wasteway.

13. The combination with a dam, of a spillway for the same extending upstream from the face of the dam and comprising side walls, a base extending laterally beyond the side walls, lateral buttresses rising from the base and supporting the side walls, and struts between the side walls.

14. The combination with a dam, of a spillway for the same extending upstream from the face of the dam and comprising a base, side walls rising from the base within its lateral margins and outwardly inclined, curtain walls extending downwardly from

the base, abutments rising from the outer margins of the base and supporting the side walls, and struts between the side walls.

15. The combination with a dam, of a narrow wasteway extending through the dam and upstream from the face of the dam to form a spillway, a roof over the spillway spaced therefrom to provide openings for the flow of water over the spillway,

inwardly swinging gates tending to close said openings, a roof for the wasteway, and an outwardly swinging gate normally tending to close the discharge end of the wasteway.

In testimony whereof I have signed my name to this specification.

JOHN F. VAUGHAN.
